Inventor

UNITED STATES PATENT OFFICE.

ANDREW J. SONNER, OF MILLTOWN, INDIANA.

HAME-COUPING.

SPECIFICATION forming part of Letters Patent No. 369,618, dated September 6, 1887.

Application filed May 27, 1887. Serial No. 239,564. (No model.)

To all whom it may concern:

Be it known that I, ANDREW J. SONNER, a citizen of the United States, residing at Milltown, in the county of Crawford and State of Indiana, have invented a new and useful Improvement in Hame-Couplings, of which the following is a specification.

My invention relates to an improvement in hame-couplings; and it consists in the construction and arrangement of the parts of the same, which will be more fully set forth hereinafter, and particularly pointed out in the claims.

The object of my invention is to provide means whereby the lower portion of a hame may be readily uncoupled and disconnected from its counterpart or construction, and dispensing with the use of buckles. I attain this object by the construction illustrated in the accompanying drawings, wherein like letters of reference indicate corresponding parts in the several views, and in which—

Figure 1 is a perspective view of my improved attachment, shown in connection with the hame. Fig. 2 is an elevation of one of the hames, showing my improvement in connection therewith. Fig. 3 is an end elevation of one of the hames. Fig. 4 is a sectional view on the line $x-x$ of Fig. 2.

A indicates the two portions of a hame, having the back irons, a , as in the usual construction. In one of the hames A a slot, A' , is formed in the face portion thereof, and in the edge thereof another slot or groove, a'' , is provided. In the slot a'' a lever, B, is mounted and secured to a fulcrum-pin, b , which is pivotally connected to the hame by means of a pin, b' , passing transversely through the pin b . The upper end of the lever B has a pin, B'' , depending downwardly therefrom into the body of the hame, which is encircled by a coiled spring, b^3 , which has bearing between the under side of the lever B at this point and the lower portion of the recess in which it is situated. This end of the lever B is slightly raised above the surface of the hame, for a purpose which will be more fully hereinafter set forth. The opposite end of the lever B is provided with a hook, b^4 , which projects down over the edge of the hame.

Secured to the lower end of the hame is a wire rod, C, which is bent into such form as to provide a space between the same and the outer

edge of the hame. The upper end of this rod C is adapted to pass into the recess A' , and to extend into said recess to such a depth as to permit the hooked end b^4 of the lever B to pass over the same, and to be released therefrom by pressing the upper end of the lever B, which slightly projects above the surface of the hame, as hereinbefore stated. The chain connected to the approximately-situated hame A is passed over the rod C through the medium of one of its links, and the two parts thus secured together, as shown in Fig. 1. By this means it will be seen that a ready connection or disconnection of the two portions of the hame may be readily obtained, and which construction is especially advantageous when it is quickly required to unharness horses for many purposes.

The novelty and utility of my improved device being obviously apparent and appreciable, it is unnecessary to further enlarge upon the same herein.

Having thus described my invention, I claim—

1. The combination, with a hame, of the spring-actuated lever B, mounted in a slot formed in one face of the hame-wood, and having its one end normally raised above the surface of said wood, and the wire C directly secured to the lower end of the hame at one end, and the opposite end adapted to pass through a slot formed in the edge of the hame to be engaged by the end of the lever B, substantially as described.

2. The combination, with a hame, of the lever B, mounted and fulcrumed in a slot formed in the face of the hame-wood, and having a hook formed on its lower end, an actuating-spring mounted under one end of the said lever and at right angles thereto, and the wire C, directly secured at its one end to the lower end of the hame, and its opposite end adapted to pass through a slot in the edge of the hame and be engaged by the hook of the lever B, substantially as described.

In testimony that I claim the foregoing as my own I have hereto affixed my signature in presence of two witnesses.

ANDREW J. SONNER.
